his Attorney.

UNITED STATES PATENT OFFICE

2,551,721

GRINDING FIXTURE FOR PIERCER PLUGS

James Borzi, Ellwood City, Pa.

Application January 27, 1950, Serial No. 140,782

4 Claims. (Cl. 51—236)

1

The present invention relates to a supporting fixture and more particularly to a supporting fixture suitable for holding a piercer point in proper position for grinding the back end thereof.

The piercer points normally used in modern tube mills are cast alloy steel. The purpose of grinding the back end of the piercer point is to smooth off the rough cast surface thereon and make the back end approximately normal to the long axis of the piercer point. The proper angularity of the back end relative to the long axis of the piercer point is necessary so that the piercing mill mandrel bar will fit flush against the piercer point and thus push it in a straight path during a piercing operation.

Prior to my invention, this grinding operation was performed by hand. The operator manually held the piercer point against the grinding wheel and rotated it by hand as the grinding operation proceeded. The hazardous nature of this operation is obvious. Any accidental mishandling of the piercer point while being ground on a high speed abrasive wheel was likely to cause serious injury to the operator himself or to workers nearby.

It is accordingly an object of my present invention to provide an adjustable supporting fixture for rotatably holding an elongated workpiece with one of its ends in contact with a rotating grinding wheel.

This and other objects will be more apparent after referring to the following specification and attached drawing, in which:

Figure 1 is a plan view;

Figure 2 is an elevational view, partly in longitudinal section; and

Figure 3 is an end view.

Referring more particularly to the drawing, reference numeral 2 indicates a rectangular shaped base plate having a center slot 4 on its under side parallel to its long axis. A plurality of elongated holes 6 are spaced in alignment along the slotted portion of the plate. The holes 6 are elongated in the direction parallel to the long axis of the slot. A cradle support 8 is welded or otherwise attached to the top surface of one end of the base directly over the slot. The support 8 consists of a short length of steel angle 10 welded or otherwise fastened in horizontal position on the top of a vertical supporting bar 12. The angle 10 is slotted as at 14 and 16 to accommodate a pair of rollers 18 which may be small radial ball bearings mounted on axles 20 which are welded or otherwise fastened to the

2

outside surface of the angle walls across the slots 14 and 16.

The base plate 2 may be fastened on a supporting platform 22 adjacent a grinding wheel 23 by nut and bolt means 24 as shown in Figure 2.

An end supporting element 26 cooperates with and is adjustably positioned behind and in alignment with the cradle 8 on plate 2. End support 26 consists of a cup 28 holding a ball bearing 30 of the radial-thrust type therein, an upright supporting plate 32 and an inverted S-shaped handle 34. Cup 28 is welded to one face of plate 32 while handle 34 is welded to the opposite face as best seen in Figure 2. Support 26 is detachably held in the base plate 2 by means of a hook projection 36 on the bottom of handle 34 which fits into any of the elongated holes 6. The hook 36 is fitted into the proper hole according to the length of the workpiece being processed.

In operation, a piercer point W is placed on the cradle 8 with its back end facing the periphery of the grinding wheel 23 and hook 36 is inserted in the appropriate hole 6. The end support 26 is then manually pushed against the grinding wheel by means of handle 34, thus engaging the nose of the piercer point in the ball bearing 30 and forcing the back end of the piercer point against the grinding wheel. The bearing support at its front end causes the piercer point W to revolve as it is being ground, resulting in a smooth back end substantially normal to the long axis of the piercer point.

While one embodiment of my invention has been shown and described, it will be apparent that other adaptations and modifications may be made without departing from the scope of the following claims.

40 I claim:

1. A grinding fixture for supporting a piercer point or the like for the grinding of one end thereof by a rotating abrasive wheel which comprises a base plate mounted adjacent said abrasive wheel, said plate having elongated holes therein spaced apart on a line extending normal to the grinding surface of said wheel, a cradle support mounted on said plate at the end thereof adjacent said abrasive wheel in line with said elongated holes, and an end supporting cup slidably mounted in one of said elongated holes adjacent said cradle support.

2. A grinding fixture as defined in claim 1 in which said cradle support includes a vertical supporting bar member rigidly affixed to said base

plate, an angle member substantially V-shaped in configuration rigidly attached at its apex to the top of said supporting bar, said angle member having openings in the side walls thereof, and rollers rotatably mounted in said openings.

3. A grinding fixture for supporting a piercer point or the like for the grinding of one end thereof by a rotating abrasive wheel which comprises a base plate mounted adjacent said abrasive wheel, a cradle support mounted on said plate at the end thereof adjacent said abrasive wheel, and an end support mounted on said base plate on the side of said cradle support remote from said grinding wheel, said end support including an upright plate member, and a cup having a radial-thrust type ball bearing therein rigidly attached to the surface of said upright plate facing said cradle support.

4. A grinding fixture for supporting a piercer point or the like for the grinding of one end thereof by a rotating abrasive wheel which comprises a base plate mounted adjacent said abrasive wheel, said plate having elongated holes therein spaced apart on a line extending normal to the grinding surface of said wheel, a cradle support mounted on said plate at the end thereof adjacent said abrasive wheel in line with said elongated holes, said cradle support including a vertical supporting bar member rigidly affixed to

said base plate, an angle member substantially V-shaped in configuration rigidly attached at its apex to the top of said supporting bar, said angle member having openings in the side walls thereof, and rollers rotatably mounted in said openings, and an end support mounted in one of said elongated holes adjacent said cradle support, said end support including an upright plate member, and a cup having a radial-thrust type ball bearing therein rigidly attached to the surface of said upright plate facing said cradle support.
